BOWLING SCORE SHEET TABLE

Royal J. MacMillan, St. Paul, Minn., assignor of
one-third to Franklyn M. Lewis and one-third
to William C. Kregel, St. Paul, Minn.

Application June 15, 1942, Serial No. 447,187

2 Claims.

5

This invention relates to a bowling score sheet table which is designed to support a series of bowling score sheets in a compartment table together with the duplicate score sheets in a manner so that the sheets may be drawn across a fixed table portion, under a cutting rule, and the duplicate sheets be wound around a roller.

A feature resides in providing a table which may be supported by any suitable standard or may be attached to a supporting means so as to hold the table at a convenient height so that the bowler can indicate the score on the bowling sheet during the process of a bowling game. While it is preferred to support the table by a standard or legs which make the whole device portable, it is apparent that the table can be supported on the wall or otherwise fixed in an operating position.

It is also a feature to provide a bowling score sheet table for holding a series of bowling alley score sheets in a storage compartment within the table and also to provide a roller in one end of the table upon which the duplicate sheets may be wound up and kept for reference for the proprietor or the bowling alley. In this manner the bowling alley proprietor can keep a record of the games played by the bowlers, while the original score sheet can be torn off and given to the bowler for a record of the game bowled.

A primary object resides in providing a compartment table having a fixed table top around which a removable frame fits and which frame forms a closure to enclose the supply of score sheets which are connected together. The score sheets are adapted to be fed over the fixed table into position to be used and then they are drawn under a cutting rule so that the top score sheet may be torn off while the duplicate sheets are wound upon a roller positioned within the compartment of the table. A removable key means is provided for operating the roller so that the bowling alley proprietor may be the only one who can operate the roller to wind or draw a new bowling sheet into operating position.

It is also a feature to provide a pressure roller which, by its own weight, rests upon the top of the sheets adjacent the cutting rule to hold the sheets in taut position on the fixed table top.

The removable frame top portion of the bowling table compartment may be locked in closed position by any suitable means (the drawing does not illustrate the locking means) or the removable frame top may be rested in position so that it may be removed whenever desired. When the removable frame top is lifted from the com-

partment portion of the table, entrance to the compartment is provided so that a new supply of bowling sheets may be placed therein and so that the duplicate sheets that are wound up on the storage roller can be removed.

These features together with other details and objects of the invention will be more fully hereinafter set forth.

In the drawing forming a part of this specification:

Figure 1 is a side view of my bowling score sheet portable table, showing the same supported by depending legs or a standard.

Figure 2 is a plan view of the same.

Figure 3 is a section on the line 3-3 of Figure 2.

Figure 4 is a section on the line 4-4 of Figure 2.

Figure 5 is a similar section to Figure 3, showing the removable frame top elevated from the main or base compartment table portion.

Figure 6 is a section on the line 6-6 of Figure 2.

Figure 7 illustrates a perspective view of the operating key for the winding roller for the duplicate sheets.

Figure 8 is a section on the line 8-8 of Figure 3.

My bowling score sheet table A is supported by the standard B which may be in the form of side leg portions or may be a standard of any suitable nature adapted to support the table A in an inclined working position at a convenient height so that the bowler may indicate the bowling scores on the sheets C which are adapted to be stretched over the fixed table top portion 10.

The table A is formed with a base portion 11 which provides a compartment 12 in which a series of original and duplicate bowling score sheets C are folded in a compact state. As the sheets are required for use they are fed out of the compartment 12 through the opening 13 and across the fixed table 10 under the cutting rule 14 and down through the slot 15 to the winding roller 16 which is provided for the duplicate sheets C'.

The roller 16 is held in the base portion 11 in the compartment 12 so that it can be rotated by a suitable key 18. One end of the roller 16 is slotted at 19 to receive the small end 20 of the key 18. The slot 19 in the end of the roller 16 is protected by the projecting boss 21 on the side of the base portion 11 so that a long peculiarly formed key 18 is the only instrument that can be used to operate the roller 16. While this illus-

trates a simple form of key means for operating the roller 16, it is apparent that any suitable means may be provided wherein a key 18 of any character is provided which is kept by the proprietor of the bowling alley so that only the proprietor can operate the roller 16. The reason that it is best that the bowling alley proprietor operate the roller 16 and not the patrons of the bowling alley, is because whenever a score sheet C has been used the proprietor only can operate the roller 16 to draw a new bowling score sheet into position on the fixed table 10. Thus the proprietor keeps a record of the games bowled and is able to keep a true and accurate record on the duplicate score sheet C' wound up and stored on the roller 16 in the compartment 12.

I provide a pressure roller 24 which is supported by the end bracket arms 25 on the pivots 26 so that the roller 24 may be raised or lowered against the sheets C and C'. This roller 24 is sufficiently weighted by the weight of the roller itself and the cross bar means 27 which connects with the arms 25 so as to provide sufficient weight to bear against the sheets C to hold them stretched taut over the fixed table portion 10. Thus the bowler can readily write upon the sheets C to indicate the scores in the various frames of the game and at the same time make a record on the duplicate score sheet C' in view of a carbon sheet 28 which extends between the original sheets C and the duplicate sheets C' so that a complete original and duplicate record is made of each and every game. The carbon sheets 28 extends transversely between the original sheets C and the duplicate sheets C'.

The roller 24 is fixed to the upper end of the removable frame table portion 30 so that when this portion of the table A is lifted from the lower portion 11 as illustrated in Figure 5, the compartment 12 is open at the lower end at 30 and at the upper end at 31. Thus a new supply of bowling sheets C may be introduced through the opening 30 to position the same in the compartment 12 and the proprietor may have access to the roller C through the opening 31. The removable frame table portion 30' extends about and around the fixed table portion 10 and is provided with depending sides 33 and 34 which are formed with rabbeted edges 35 and 36, respectively, which are adapted to fit into the rabbeted edges 37 and 38 of the lower table portion 11.

The removable table frame portion 30' is illustrated in closed position in Figure 3, and in partially open position in Figure 5. The frame portion 30' is formed in a unit so that it can be lifted bodily away from the lower portion 11 as set forth. When the portions 11 and 30' are fitted together they form the complete table A with the compartment 12 in the same in which the supply of bowling score sheets C and the storage winding roller 16 are positioned. Thus the supply of bowling score sheets are concealed within the com-

partment 12 as well as the roller 16 when the table A is closed and in operating position and if it is desired a suitable lock, not shown in the drawing, can be provided to hold the lower portion 11 and the top frame portion 30' together to close the bowling score sheet table A.

My bowling score sheet table A is of a simple construction and may be formed of wood or any other suitable material so as to provide a base compartment portion 11 with the fixed table 10 and the top frame portion 30' which may be easily lifted to give access to the compartment 12 of the table A.

I claim:

1. A bowling score sheet table, comprising a baseboard, leg means supporting said board at an angle to the horizontal, low side portions secured to the side edges of the board and a bottom portion of considerably less height than the side portions connecting them and united therewith and with the lower edge of the baseboard for forming a shallow chamber open at its upper end and adapted to receive and hold a supply of continuously united score sheets, a roller removably carried by said side portions, and said roller adapted to progressively wind up the score sheets, means forming a top wall over said chamber having depending front and rear walls, the rear wall for closing the open end of said chamber and the front wall adapted to engage the short front wall of the box-like structure, a plate forming part of said top wall automatically held in position when set upon the base and between the side walls, and slotted guides in said top wall for permitting the score sheet material to be drawn over the same and upon the roller.

2. A bowling score sheet table, comprising a baseboard, leg means supporting said board at an angle to the horizontal, low side portions secured to the side edges of the board and a bottom portion of considerably less height than the side portions connecting them and united therewith and with the lower edge of the baseboard for forming a shallow chamber open at its upper end and adapted to receive and hold a supply of continuously united score sheets, a roller removably carried by said side portions, and said roller adapted to progressively wind up the score sheets, means forming a top wall over said chamber having depending front and rear walls, the rear wall for closing the open end of said chamber and the front wall adapted to engage the short front wall of the box-like structure, a plate forming part of said top wall automatically held in position when set upon the base and between the side walls, slotted guides in said top wall for permitting the score sheet material to be drawn over the same and upon the roller, and a weighted roller having arms pivotally connected with the outside of said cover plate and adapted to engage and tension the united score sheets.

ROYAL J. MACMILLAN.
